TEACHING AID FOR DEMONSTRATING DRIVEN HARMONIC MOTION

Roger D. Stephenson, Overland Park, Kans., assignor to
Physics Apparatus Research, Inc., Overland Park, Kans.

Filed June 16, 1972, Ser. No. 263,441

Term of patent 14 years

Int. Cl. D19—07

U.S. Cl. D25—1 R

Fig. 1.

Fig. 2.

Fig. 3.

Fig. 4.

Fig. 5.

FIG. 1 is a front elevational view of a teaching aid for demonstrating driven harmonic motion showing my new design;

FIG. 2 is a side elevational view of the invention taken from the left side of FIG. 1;

FIG. 3 is a top plan elevational view of the invention;

FIG. 4 is a side elevational view taken from the right hand side of device shown in FIG. 1; and

FIG. 5 is a rear elevational view of the invention shown in FIG. 1.

I claim:

The ornamental design for a teaching aid for demonstrating driven harmonic motion, as shown and described.
